UNITED STATES PATENT OFFICE.

RUBEN E. JOHNSON, OF BREMERTON, WASHINGTON.

PUMP.

1,369,666.

Specification of Letters Patent. Patented Feb. 22, 1921.

Application filed May 29, 1920. Serial No. 385,249.

To all whom it may concern:

Be it known that I, RUBEN E. JOHNSON, a citizen of the United States, residing at Bremerton, in the county of Kitsap and State of Washington, have invented new and useful Improvements in Pumps, of which the following is a specification.

This invention relates to a fuel pump, more particularly designed for Diesel and semi-Diesel engines, the principal object of the invention being to provide a duplex pump for pumping two different kinds of fuel to the engine.

Another object of the invention is to provide valve means for controlling the flow of each fuel to the pump.

A further object of the invention is to provide means for adjusting the quantity of fuel delivered by the pump.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a section through a part constructed in accordance with my invention, the section being taken on line A—A of Fig. 2.

Fig. 2 is a side view with parts in section.

Fig. 3 is a plan view.

In these views 1 indicates the pump body, which is formed with two cylinders, one being shown at 2. Each cylinder is occupied by a vertically adjustable sleeve 3, the upper end of which has screw threaded engagement with the upper part of the body, as shown at 4. The upper part of each sleeve is of square shape in cross section and a worm wheel 5 has a square opening slidably engaging said square part, the wheel being held against transverse movement by means of the cap 6 which is bolted to the body. These parts are so arranged that the wheel may rotate and thus rotate the sleeve to adjust it longitudinally. The lower part of this sleeve is provided with the ports 7 which are adapted to engage with the grooves 8 formed in the walls of the cylinder, these grooves being connected with the

inlet passage 9 and the outlet passage 10. A chamber 11 forms a part of the passage 9 and this chamber is connected by a port 12 with a chamber 13, surrounding the central part of the sleeve so that some of the fuel will pass into said chamber 13 and lubricate the movable parts, the oil being passed to the interior of the sleeve by means of the small ports 14 and the groove 15.

A valve sleeve 16 passes through the chamber and this sleeve carries the valve member 17 which controls the ports 18 in said sleeve and thus regulates the flow of fuel through the passage 9. The valve member is normally held closed by means of the spring 19 and is opened by means of the arm 20 carried by the shaft 21 and having the regulating screw 22 thereon for engaging the top of the valve member. As will be seen the regulating arms for the two valve members are located on different shafts and these shafts may be connected with a suitable governor or may be actuated by hand to control the flow of the different fuels to the pumps. A check valve 23 is located in each outlet passage 10. The pump plungers 24 have their upper ends secured to a cross head 25 so that they reciprocate in the sleeve in unison. The cross head is carried by a centrally located rod 26 which passes through the body and is normally held in lowered position by a spring 27. This spring holds the lower end of the rod against a cam 28 which is carried by a shaft 29 journaled within the lower part of the body and is adapted to be rotated from any suitable source of power. The cam is provided with a clutch part 30 which is pressed, by a spring 31, against the clutch sleeve 32 carried by the shaft. By this arrangement of parts the cam will only be rotated in one direction by the shaft for when the shaft is rotated in an opposite direction the cam part of sleeve 32 will force the cam toward the right and compress the spring, the pressure of the spring pressed rod 26 on the cam preventing the cam from rotating.

The worm wheels 5 are engaged by the wheels 33 carried by the shaft 34 which is adapted to be rotated from any suitable source.

It will be seen that when the pump plungers are being reciprocated the fuel will be drawn into the chamber 11 by the suction and will pass from this chamber through the valve member, if the same is open, into

the cylinder to port 7. On the compression stroke the fuel will be forced through the passage 10 to the engine. The quantity of fuel being injected into the engine may be varied by the sleeve 3 as by adjusting said sleeve longitudinally the ports 7 therein will be adjusted in relation to the end of the plunger and thus regulate the quantity of fuel being delivered by the plunger. If the sleeve is raised the plunger will close the ports 7 thus cutting off the escape of the remaining fuel in the cylinder and this fuel will act as a cushion for the plunger.

A governing of the pumps is accomplished independently through rods 21 which actuate the arms 20. If it is desired, as in starting, to use more volatile oil the arm acting on the valve member for the less volatile oil is depressed so as to hold this valve member open and permit the opposite pump for the volatile oil to operate without interference on the part of the other pump. After the engine is started and it is desired to use the less volatile oil then the opposite arm is depressed to open the valve of the volatile oils and permit the pump therefor to run idle.

The parts 12, 13, 14 and 15 also serve to drain the fuel oil which might pass the plunger 24 into the suction chamber.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. An apparatus of the class described comprising a cylinder, having inlet and outlet ports, a sleeve having inlet and outlet ports located in the cylinder, a piston in the sleeve, means for reciprocating the piston, a portion of said sleeve having screw threaded engagement with the upper part of the cylinder and means for rotating the sleeve to adjust it longitudinally within the cylinder,

such means consisting of a worm wheel having sliding engagement with the sleeve and a worm shaft engaging said wheel.

50

2. An apparatus of the class described comprising a body having a pair of cylinders therein, a longitudinally adjustable sleeve in each cylinder having inlet and outlet ports therein, the cylinder having inlet and outlet passages communicating with said ports, a cross head connected with the plungers, means for reciprocating the cross head, a spring controlled valve for normally closing the inlet leading to each cylinder and means for actuating said valves independently of each other.

55

3. An apparatus of the class described comprising a body having a pair of cylinders therein, a longitudinally adjustable sleeve in each cylinder having inlet and outlet ports therein, the cylinder having inlet and outlet passages communicating with the ports, a plunger in each sleeve, a cross head connected with the plungers, a rod connected with the cross head, a power shaft, a cam thereon engaging the lower end of the said rod, spring means for holding the rod in engagement with the cam and independently actuated valves for controlling the inlet passages of the cylinders.

60

4. An apparatus of the class described comprising a body, a pair of cylinders therein, inlet and outlet passages for the cylinders, a longitudinally adjustable sleeve in each cylinder having inlet and outlet ports therein, a plunger in each sleeve, a cross head connected with the plungers, a rod connected with the cross head, a power shaft, a cam thereon, spring means for holding the end of the rod in engagement with the cam, clutch means for connecting the cam with the shaft for driving the cam in but one direction and independently operated valves for controlling the inlet passages to the cylinders.

65

In testimony whereof I affix by signature.

RUBEN E. JOHNSON.
